UNITED STATES PATENT OFFICE.

WILLIAM E. URSCHEL, OF VALPARAISO, INDIANA.

BERRY-STEM REMOVER.

No. 918,933.

Specification of Letters Patent. Patented April 20, 1909.

Application filed June 22, 1908. Serial No. 439,691.

To all whom it may concern:

Be it known that I, WILLIAM E. URSCHEL, a citizen of the United States, residing at Valparaiso, county of Porter, and State of Indiana, have invented certain new and useful Improvements in Berry-Stem Removers, of which the following is a specification.

My invention relates to improvements in devices adapted to remove the stems from berries, and consists in a machine for the purpose mentioned which will be hereinafter fully described.

The preferred form of my invention is illustrated in the accompanying drawings forming a part of this specification and in which,

Figure 1 is a perspective view of the complete machine, Fig. 2 is a detail perspective view of a bevel-gear housing, Fig. 3 is a bottom elevation showing the cutting mechanism of the machine, Fig. 4 is a central vertical section of the body portion of the machine, Fig. 5 is a horizontal transverse section taken on the line z of Fig. 4, Figs. 6 and 7 are horizontal transverse sections taken on the lines y and z respectively, of Fig. 4, and Fig. 8 is a detail perspective view.

Referring now to the drawings, 1 indicates the body or frame of the machine, and 2, 30 legs adapted to support the body 1. Bearings 3 and 4 are adapted to receive a shaft 5 to which a crank 6 is secured, the crank 6 being provided with a handle 7 as shown. The bearing 3 is positioned as shown, and the bearing 4 is formed in the upper portion of a bracket 8. The bracket 8 is secured to a transverse horizontal partition 9 by screws 10. Portions of the body sides and the partition 9 form a suitable hopper for the berries 11. A bevel-gear 12 is rigidly secured to the shaft 5 and is adapted to drive the bevel-pinion 13 secured to the shaft 14. The shaft 14 is provided with an integral crank pin 15 and is journaled in the bracket 10 and in a plate 16 diametrically disposed across the circular opening 17 in the bottom of the body 1. A suitably shaped housing 18 provided with a slot 19 is adapted to protect the bevel-gears 12 and 13 as shown in Fig. 2. 45 A stationary internal gear 20 whose axis coincides with the axis of the shaft 14, is rigidly secured to the partition 9 by means of the screws 21. A spur-gear 22 is provided with lugs 23 which are rigidly secured to vertical rods 24, which rods are in turn rigidly secured to the member 25. The mem-

ber 25 is provided with a bushing 26 in which the crank-pin 15 is journaled. The gear 22 is arranged in such a manner that its axis coincides with the axis of the crank-pin 15. 60 The gears 20 and 22 are adapted to mesh a shown.

When the shaft 14 is rotated the gear 22 revolves bodily in the circle described by the crank-pin 15 in its revolution, but rotates on its own axis only a small part of a revolution. The vibratory and slow rotative movement given to the member 25 and chains connected therewith, causes berries 11 to have a rolling movement in all directions and a slow revolving movement on the stationary radially slotted member 27 secured to the blocks 28 by means of screws 29. A guide 30 is riveted to the rods 24 at the points 31, and is provided with a large aperture 32 and a washer 75 33 adapted to cover the aperture 32. Concentric rings 34 and 35 are secured to lips 36 and 37 respectively, as shown. Radial rods 38 are suitably secured to the rings 34 and 35 and are adapted to support circular rods 39 80 which are equally spaced by spiral wires 40. Short chains 41 depending from the rods 39 are adapted to support a plurality of chains 42 as shown in detail in Fig. 8. The chains 42 form a flexible covering adapted to conform to all sizes of berries, hence, causing all the berries to roll on the member 27. The guide 30 leads to the opening 43, the berries falling on the member 27 as indicated by a berry 44. For clearness of illustration, the 85 slots in the member 27 are not shown in Figs. 5, 6 and 7. After the berries have made a complete revolution on the member 27, they are deflected through the opening 45 in the ring 35 by means of the spring 46 which is 90 secured to the ring 34 at the point 47. The berries are then adapted to pass through the central opening 48 in the member 27 and through the opening 17 in the body 1 into a suitable receptacle beneath the machine, not 95 shown. The rotary cutter for removing the berry stems which extend downwardly through the slots in the member 27, comprises a plurality of knives 49 having bevel cutting edges 50. The knives 49 are secured 100 to a flat ring 51 and to a diametrically disposed plate 52 by means of the rivets 53. The plate 52 is secured to the shaft 14 and is adapted to rotate therewith. The opening 54 in the base of the body 1 is provided to 110 permit the berry stems to escape.

Having described my invention what I

claim as new, and desire to secure by Letters Patent, is:

1. In a device of the class described, a frame, a shaft journaled in said frame, a 5 crank formed on said shaft and means for driving said shaft, in combination with a horizontal disk rotatably mounted on said crank, an internal gear fixed to said frame, a spur gear rigidly connected to said disk and 10 meshing with the first said gear, a pair of concentric annular members depending from said disk and forming an annular raceway between them, a stationary slotted plate arranged beneath said members and forming a 15 bottom for said raceway, and a knife fixed to said shaft and rotatable therewith beneath said slotted plate, substantially as described.

2. In a device of the class described, a frame, a shaft journaled in said frame, a 20 crank formed on said shaft and means for driving said shaft in combination with a disk rotatably connected to said crank, an internal gear fixed to said frame, a spur gear rigidly connected to said disk and meshing with 25 the first said gear, a pair of concentric annular members depending from said disk and forming an annular raceway between them, a stationary slotted plate arranged beneath said members and forming a bottom for said 30 raceway, means for feeding berries to said raceway, a flexible device for holding the berries in contact with said slotted plate and a rotary knife arranged beneath said plate and coacting therewith, substantially as de- 35 scribed.

3. In a device of the class described, in combination with a frame, a drive shaft journaled therein, means for driving said shaft, a crank formed on said shaft, a hopper 40 and a guide, a rotary member mounted on said crank, an internal gear secured to a portion of said hopper, a spur gear adapted to mesh with said internal gear and rigidly secured to said rotary member, the axis of 45 said spur gear being coincident with the axis of said crank, concentric rings secured to said member, chains suspended between said rings, a slotted member secured to said frame beneath said rings, and a rotary cutter 50 arranged beneath said slotted member and adapted to coact therewith, substantially as described.

4. In a device of the class described, in combination with a frame, a drive shaft jour-

naled therein means for driving said shaft, 55 a crank formed on said shaft, a rotary member mounted on said crank, an internal gear fixedly mounted in said frame, a spur gear adapted to mesh with said internal gear and rigidly secured to said rotary 60 member, concentric rings secured to said member, a frame arranged between said rings, a plurality of chains suspended from said frame, a slotted member secured to said frame beneath said rings, and a rotary 65 cutter arranged beneath said slotted member and adapted to coact therewith, substantially as described.

5. In a device of the class described, in combination with a frame, a drive shaft 70 journaled therein means for driving said shaft, a crank formed on said shaft, a rotary member mounted on said crank means for slowly rotating said member as the shaft is rapidly rotated, concentric rings depending from said member, radial rods and circular rods supported by said rings, flexible members depending from said rods, horizontally disposed members suspended from the first said flexible members, a slotted member 80 secured to said frame beneath said rings, and a rotary cutter arranged beneath said slotted member and adapted to coact therewith, substantially as described.

6. In a device of the class described, a 85 frame, a shaft journaled in said frame, a crank formed on said shaft and means for driving said shaft, in combination with a rotary member mounted on said crank, means for slowly rotating said member as the 90 shaft is rapidly rotated, concentric rings depending from said member forming a raceway for berries between them, a slotted member secured to said frame beneath said rings and provided with a central aperture, a rotary 95 cutter arranged beneath said slotted member, means for feeding berries to said raceway and means for guiding the berries from said raceway to said aperture, substantially as described.

In testimony whereof I have signed my name to this specification in the presence of two subscribing witnesses.

WILLIAM E. URSCHEL.
